J. E. JOHNSON

INDICATING FUSE PLUG

Filed Nov. 27, 1920

Fig. 1

Inventor:
John E. Johnson,

By: Albert Scheibh, Atty.

UNITED STATES PATENT OFFICE.

JOHN E. JOHNSON, OF DE KALB, ILLINOIS, ASSIGNOR OF ONE-HALF TO C. EDWARD LINDGREN, OF DE KALB, ILLINOIS.

INDICATING FUSE PLUG.

Application filed November 27, 1920. Serial No. 426,794.

To all whom it may concern:

Be it known that I, JOHN E. JOHNSON, citizen of the United States, residing at De Kalb, Illinois, have invented certain new and useful Improvements in an Indicating Fuse Plug; and I do hereby declare the following to be a full, clear, and exact description of the invention, such as will enable others skilled in the art to which it

10 appertains to make and use the same.

My invention relates to fusible devices as used for protecting electric circuits, its general object being that of providing simple, effective and inexpensive means for indicating when the fuse in the device has blown. More particularly, my invention relates to electric fuse plugs and aims to provide simple and inexpensive means for instantly affording a visual indication of 20 the blowing of the fuse within a plug, so that the burnt out fuse plugs can readily be detected without the necessity of previously handling or testing the same. Furthermore, I aim to provide indicating means 25 which can readily be adopted in the construction of standard types of fuse plugs, and to arrange these in such a manner that they will not in any way interfere with the fuse plug either as to its installation or 30 otherwise. Still further and more detailed objects will appear from the following specification and from the accompanying drawings, in which—

Fig. 1 is a central and longitudinal section through a fuse plug embodying my invention and showing the same with the fuse intact.

Fig. 2 is a plan view of the same taken after the indicating film has been ruptured 40 by the burning of the fuse.

Fig. 3 is a transverse section through the plug of Fig. 1, taken from the lower surface of the opaque indicating film.

Fig. 4 is a section similar to the upper 45 portion of Fig. 1, but taken after the fuse has blown.

In the embodiment of the drawings, I am showing my invention as applied to a fusible device of the type popularly known 50 as a fuse plug and adapted for insertion in a receptacle of the screw-shell type. This fuse plug has a hollow porcelain body 1 carrying an axially disposed terminal 2 and also carrying a peripheral and spirally 55 grooved terminal 3. The porcelain body 1

has a chamber 4 open at the rear end of the plug and housing a fuse 5 which has its ends respectively soldered to the terminals 2 and 3. This fuse is desirably bowed so as to present a bend or bight directed towards 60 the cap of the plug, and this cap desirably includes a substantially transparent mica disk 6 clamped in position by a metal collar 7.

Thus arranged, the fuse can ordinarily 65 be seen more or less distinctly through the cap 6, depending both on the transparency of the mica and the lighting available. However, the clearness with which the fuse may be viewed through the cover is not 70 always adequate for determining whether or not the fuse is still in operative condition, so that a visual inspection is not ample for this purpose but in a large share of cases has to be supplemented by a removal and 75 testing of the fuse plug. Consequently, the electrician who wants to locate a burnt-out fuse in a cabinet containing a group of such fuse plugs is obliged to remove and test one after another of the plugs before he 80 finds the one containing the ruptured fuse. This consumes valuable time and also is difficult for the ordinary user who has no facilities for testing such plugs.

To avoid such a loss of time, as well as 85 the delay and expense in attending to the same, I provide a screen which is normally intact but which is adapted to be ruptured by the heat of the blowing fuse, so that the imperfect condition of this screen will 90 instantly indicate that it is in a plug in which a fuse has blown. Moreover, I desirably employ for this purpose a screen which normally conceals the interior of the chamber 4 entirely from view and which 95 readily reflects exterior light, so as to increase the visual difference between the normal screen and a ruptured one. If this screen touched the mica cap, such contact might cool the heated screen sufficiently to 100 interfere with an adequate rupturing of the film by the heat of the blowing fuse, hence I desirably space the screen from the mica cap.

To accomplish these purposes at a trifling 105 addition in the cost of construction over the ordinary fuse plug of this type, I place a disk 8 of a suitable thermally rupturable material over the mouth of the body 1 of the plug before slipping the 110

mica cover disk 6 and the annular collar 7 in position, and I also desirably space the screen 8 from the mica cover by an annular washer 9 which may also be of mica. For the 5 screen 8, I desirably use a thin film of metal having a low melting point such as a tin foil or lead foil, and I have found in practice that the heat generated during the blowing of an ordinary fuse will readily 10 melt a portion of such a metal film so as to produce an aperture in this screen. Consequently, the screen which normally presents a uniformly opaque face towards the mica cover 6 will appear punctured after the 15 manner of Fig. 2 when the fuse has blown, thereby instantly indicating which one of a group of plugs is no longer in operative condition.

To make this visual indication all the 20 more clearly apparent, I desirably employ a screen having a good reflecting surface on the side towards the mica. Such a reflecting surface may be afforded either by the metal of the foil itself, or by a glossy 25 colored coating on the latter after the manner commonly used on the foils employed over the stoppers of bottles. Since such a polished film readily reflects light, the difference between the light thus reflected by 30 the remaining portion of a punctured film and the necessarily darkened interior of the chamber 4 will be all the greater, as indicated in Fig. 2 of the drawings, thus increasing the readiness with which the spoilt 35 fuse plug can be detected.

To insure an instantaneous rupturing of such an opaque film, I desirably bring the fuse fairly close to the latter, and I may further increase the certainty of action by 40 employing a fuse having a portion 10 of reduced cross section adjacent to the screen or film, so as to cause the fuse to blow at a point so close to the film that the heat of the blowing will be sure to melt a portion 45 of the screen. In practice, the resulting rupture may also be assisted by the explosive action of the metal of the ruptured

fuse; and by spacing the film from the mica cover in the manner described, I prevent any cooling action of the mica from 50 interfering with the producing of a perforation of considerable size in the film. At the same time, by employing an incombustible material such as metal for such as metal for such a film or screen, I avoid the production of any added flame to which the 55 underwriters might object.

However, while I have illustrated and described my invention as embodied in a highly desirable form in which the rupturable screen is in the shape of a disk and is made of a metal foil, and in which this screen is spaced by an annular washer from the cover of a fuse plug of the screw type, I do not wish to be limited to these or other 60 details of the construction and arrangement here disclosed, since numerous variations might obviously be made without departing from the spirit of my invention or from the appended claims. 70

I claim as my invention:—

1. A fuse plug having a cavity therein, a fuse mounted within the cavity, and a metal foil stretched across the mouth of the cavity and clamped substantially at its periphery against the fuse plug. 75

2. In a fusible plug, a casing adapted to house a fuse and having an aperture, a thermally fusible film spanning the aperture, and a covering of transparent incombustible and infusible material disposed across the aperture outside of the said film. 80

3. In a fuse plug, a casing housing a fuse, a mica disk entirely closing the mouth of the casing, a disk of fusible material disposed between the mica disk and the fuse and spaced from both of the latter and presenting a light-reflecting surface towards the mica disk, and single means for clamping both disks in their said position. 85

Signed at De Kalb, Illinois, November 24th, 1920. 90

JOHN E. JOHNSON.
